LUBRICANT RESERVOIR AND FOLLOWER CONSTRUCTION

Iver B. Nielsen, Bryan, Ohio, assignor to The Aro Equipment Corporation, Bryan, Ohio, a corporation of Ohio

Application July 18, 1932. Serial No. 623,196

9 Claims. (Cl. 221—47.3)

An object of my invention is to provide a lubricant reservoir and a follower therein of simple, durable and inexpensive construction with mechanism for moving the follower in one direction for discharging the contents of the lubricant reservoir therefrom and moving it in an opposite direction for drawing a fresh supply of lubricant into said reservoir.

Still a further object is to provide means for introducing compressed air into the reservoir behind the follower to cause expelling movement of the follower and to provide spring means to return the follower, a release valve being provided which when opened will allow the spring to cause such return.

Still a further object is to provide a means of return which is operated by air, the means being of the Venturi type.

Another object is to provide the Venturi means in a detachable handle and to provide a collapsible connection between the follower and the handle so that the handle can be detached and used for returning the follower instead of using the Venturi means.

With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 shows a lubricant gun having a reservoir thereon partly broken away and shown in section to illustrate one form of my invention.

Figure 2 is an enlarged sectional view on the line 2—2 of Figure 1; and

Figure 3 is an enlarged sectional view somewhat similar to the right end of Figure 1 showing a modified construction.

On the accompanying drawing, I have used the reference character A to indicate generally a lubricant gun. The gun A has a reservoir 10 and a piston-like follower 12 therein. The reservoir itself is in the form of a cylinder.

The lubricant gun A includes a booster mechanism 14 and an operating handle 16 therefor and also a discharge fitting 18 which form no part of my present invention.

On the rearward end of the reservoir cylinder 10, I provide a head 20. A spring 22 is connected with a screw eye 24 in the head 20 and with a perforated ear 26 of the follower piston 12. The normal tendency of the spring 22 is to compress whereby to constrain the piston 12 to remain adjacent the head 20.

In the head 20, I provide an inlet check valve 28 and a suitable dust cap 30 therefor. The valve 28 is similar to a tire valve so that a tire chuck can be engaged therewith for introducing compressed air into the cylinder 10 behind the piston 12. This places the contents of the reservoir ahead of the piston under pressure to feed it to the booster 14 or to directly discharge it through the fitting 18 if desired.

As shown in Figure 2, the head 20 is also provided with a relief valve 32. The valve 32 comprises a body with a seat 34 therein and a spring pressed valve member 36 normally against the seat and unseated only when excess pressure is introduced into the reservoir and overcomes the tension of a spring 38 behind the valve member.

A release valve 40 has a pointed end 42 coacting with a seat 44. When it is desired to release the pressure in the reservoir 10 and allow the spring 22 to retract the piston 12, this valve 40 may be rotated to the open position.

In operation, the discharge end of the grease gun A is placed in a supply of lubricant and then the valve 40 opened which will allow the spring 22 to compress and draw in a new supply of lubricant. The valve 40 may then be closed and the reservoir 10 filled with air through the fitting 28 until the release valve 32 opens. The tire chuck may then be removed from the fitting 28 and the cap 30 placed in position.

Instead of a spring return, I have shown in Figure 3 a Venturi type of return. A handle 46 is screw threaded into the head 20a (all parts in this figure similar to the parts of Figures 1 and 2 will be given the same reference numerals with the addition of the character a). The handle 46 is provided with a tapered end 48 adapted to seat against a seat 50 for sealing the handle relative to the reservoir 10a.

Within the handle 46, I provide a release valve 52 having a pointed end 54 seated against a seat 56. A Venturi nozzle 58 extends into a Venturi bore 60 of the handle and is adjustable relative to the bore. It will be noted that the nozzle 58 is screw threaded relative to the handle and its upper end is slotted at 62 so that it can be engaged by a screw driver and rotated. The upper end is covered by a sleeve-like cap 64 with packing 66 interposed between the cap and a shoulder of the nozzle 58. This cap is removed to effect adjustment and is then tightened in position to tighten the packing 66.

A compressed air reception fitting 68 communicates with the upper end of the sleeve-like cap 64 and is capped as indicated at 70. The cap 110

70 may be removed and a compressed air hose connected with the fitting 68 for operating the Venturi mechanism.

The Venturi bore 60 communicates by means of a passageway 72 with a fitting 74, which in turn communicates with the interior of the reservoir 10a behind the piston 12a. It will be obvious that when it is desired to re-fill the reservoir 10a, the release valve 52 may be opened for releasing compressed air from the reservoir and the compressed air can be introduced through the nozzle 58 for drawing air from the passageway 72 through the bore 60 and discharging it past the release valve 52. This creates a vacuum in the reservoir 10a for retracting the piston 12a.

If desired, the piston 12a can be retracted manually. To do this, the handle 46 is disconnected from the head 20 by rotation since the parts are screw threaded together as illustrated. The handle 46 may then be pulled outwardly relative to the reservoir 10a, whereupon a chain connection 76 between the fitting 74 and a fitting 78 of the piston 12a will be pulled to taut position and can then be further pulled for retracting the piston 12a manually.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a lubricant reservoir and follower construction, a reservoir for lubricant, a piston-like follower therein, a head on said reservoir, means for introducing air under pressure through said head into said reservoir behind said follower, a handle detachable from and sealed relative to said head and a collapsible connection between said handle and said follower.

2. In a lubricant reservoir and follower construction, a reservoir for lubricant, a piston-like follower therein, a head on said reservoir, means for introducing air under pressure through said head into said reservoir behind said follower, a handle mounted on said head, a release valve in said handle and Venturi means in said handle for withdrawing air from the space in said reservoir behind said follower.

3. In a device of the class described, a reservoir, a follower therein, means for introducing compressed air to said reservoir behind said follower, means for releasing such air, a handle on said reservoir and Venturi means in said handle for creating a vacuum in said reservoir behind said follower.

4. In a device of the class described, a reservoir, a follower therein, means for introducing compressed air to said reservoir behind said follower, means for releasing such air, a handle on said reservoir, Venturi means in said handle for creating a vacuum in said reservoir behind said follower, said handle being detachable and sealed relative to said reservoir and a collapsible connection between said handle and said follower.

5. In a device of the class described, a reservoir, a follower therein, means for introducing compressed air to said reservoir behind said follower to cause movement thereof in a forward direction, means for releasing such air, a handle on said reservoir, Venturi means in said handle for creating a vacuum in said reservoir behind said follower, said handle being detachable relative to said reservoir and means for connecting said handle with said follower to pull the follower in a rearward direction.

6. In a device of the class described, a reservoir, a follower therein, means for introducing compressed air to said reservoir behind said follower, means for releasing such air, a handle on said reservoir and venturi means in said handle for creating a vacuum in said reservoir behind said follower, said Venturi means including an inlet for compressed air and a cap for said inlet when said Venturi means is not in operation.

7. In a device of the class described, a reservoir, a follower therein, means for introducing compressed air to said reservoir behind said follower, means for releasing such air, a handle on said reservoir, a release valve and Venturi means in said handle, said Venturi means discharging through said release valve when it is open to create a vacuum in said reservoir behind said follower.

8. In a lubricant reservoir and follower construction, a reservoir for lubricant, a piston-like follower therein, a head on said reservoir, means for introducing air under pressure into said reservoir behind said follower, a handle detachable from and sealed relative to said head and a collapsible connection between said handle and said follower.

9. In a lubricant reservoir and follower construction, a reservoir for lubricant, a piston-like follower therein, a head on said reservoir, means for introducing air under pressure into said reservoir behind said follower, a handle screw-threadedly engaged with said head and sealed relative thereto when in its screw-threaded relation thereto and a collapsible connection between said handle and said follower.
